UNITED STATES PATENT OFFICE.

JOHN F. WILSON, OF CAMDEN, NEW YORK.

BELT-TIGHTENER.

SPECIFICATION forming part of Letters Patent No. 250,617, dated December 6, 1881.

Application filed July 28, 1881. (No model.)

To all whom it may concern:

Be it known that I, JOHN F. WILSON, of 5
Camden, in the county of Oneida and State of
New York, have invented a new and Improved
Belt-Tightener, of which the following is a full,
clear, and exact description.

The object of my invention is to provide a
new and improved device for tightening belts,
especially elevator-bucket belts, and giving
10 them the required tension.

The invention consists of two frames, which
have screws mounted in their ends for drawing
these frames together or separating them,
on which frames serrated or ribbed segmental
15 interchangeable belt-clamping blocks, with
handles for operating them, are pivoted, which
pivots can be withdrawn to remove the clamping-
blocks from the frame.

In the accompanying drawings, Figure 1 is a
20 front elevation of my improved belt-tightener.
Fig. 2 is a longitudinal sectional elevation of
the same on the line *y y*, Fig. 1. Fig. 3 is a
horizontal sectional view of the same on the
line *y y*, Fig. 1.

25 Similar letters of reference indicate corresponding parts.

A is the elevator-shaft, through which the
belt B passes. The plates or frames C' C² are
provided with end plates or flanges, D' D², on
30 the front side, and with transverse projecting
strips E E on the rear side, these strips E E
to rest against the side of the shaft-casing.
The plates or frames C' C² are provided on the
front with raised parts F' F², which are rough-
35 ened, toothed, or fluted. The upper frame, C',
is provided at each end, top, and bottom with
lugs G, having smooth apertures, and the lower
frame, C², is provided with the nuts H, pivoted
in lugs or projections J J at the ends of the
40 frame or plate C². A screw, K, passes through
the lugs G G and through the nuts H at each
side of the apparatus, and this screw is pro-
vided at its upper end with a hand-wheel, L,
by means of which it can be turned and the
45 frames C' C² drawn together or separated.

Plates or blocks M' M², with a serrated,
toothed, or ribbed curved surface, are provided
with a handle-frame, N, and are eccentrically
pivoted to the end plates or flanges, D' D², by
50 means of the pintles O O, which pass through
the transverse bars P P of the frame N, and
are surrounded by spiral springs Q, which press

these pintles into the apertures in the flanges
D' D².

The pintles O O are provided with buttons 55
or disks R or equivalent at their inner ends,
and the plates or blocks M' M² are provided
with a stud or projection, R', on their inner
surface, against which projection the buttons
R strike when the pintles are drawn inward 60
too far. A slotted quadrant, strip, or plate,
S, is loosely mounted on each pintle O, and is
held on one of the transverse bars P of the
frame N by means of a screw, T, and a milled
nut, V. 65

The teeth or ribs of the upper frame, C', and
of the corresponding plate or block, M', are to
be inclined downward, and the teeth or ribs of
the lower frame and block or plate are to be
inclined upward. 70

The end plate or flange, D' or D², at one end
of the frames C' or C², is made removable, and
for this purpose has apertured lugs W W, which
are passed through apertures in the plate or
frame C' or C², upon which a tapering pin, Y, is 75
passed through the apertures of these lugs to
hold this end plate on the frame-plate C' or C².

The belt-tightener is used in the following
manner: The two frames C' C² are placed
against the casing of the elevator-shaft, as 80
shown, and the ends of the belt B are passed
in between the raised and roughened parts
F' F² of these plates and the corresponding
curved and roughened plates or blocks M' M²,
the handle-frames of which are then turned, 85
as indicated by the arrows, whereby the belt
ends will be firmly clamped in between the
frames C' C² and the clamping-plates M' M².
The screws K are then turned so as to draw
the frames C' C² together, whereby the ten- 90
sion of the belt is increased. The ends of the
belt are then united, and the belt-tightener
must be removed. To accomplish this the but-
tons R R are pressed toward each other, where-
by the ends of the pintles O are withdrawn 95
from the apertures or recesses in the end plates,
thus permitting the clamping blocks or plates
to be removed from the bed-plates. The pins
Y are then withdrawn, the corresponding end
plates removed, and the bed-plates withdrawn 100
from under the belt.

Instead of passing the ends of the belt in
between the curved clamp-plates and the bed-
plates, the bed-plates may be first passed under

the belt, and the clamp-plates may then be passed in between the end plates or flanges of the bed-plates.

The nuts H are pivoted, so that there will not be any undue twisting strains on the lower bed-plate or frame, C², and to avoid cramping of the screws.

The slotted plates S are so adjusted that their ends will rest against the belt when the same is clamped tight enough, and thus prevent injury to the ends of the belt by an undue pressure; and, besides, if the clamps are turned in the direction of the arrows too far, the teeth will not catch on the belt.

15 One screw K can be advanced faster than the other, for the purpose of bringing the ends of the belt into line.

Having thus described my invention, I claim as new and desire to secure by Letters Patent—

20 1. A belt-tightener made substantially as herein shown and described, and consisting of two bed-plates united by screws and provided with removable and interchangeable belt-clamping devices, as set forth.

25 2. In a belt-tightener, the combination, with the bed-plates C' C², of the screws K, the removable and interchangeable belt-clamping devices M' M², and the gages S, substantially as herein shown and described, and for the

30 purpose set forth.

3. In a belt-tightener, the combination, with the bed-plate C', provided with smooth apertured lugs G G, and the bed-plate C², provided

with the pivoted nuts H, the screws K, and the belt-clamping devices M' M², substantially 35 as herein shown and described, and for the purpose set forth.

4. In a belt-tightener, the combination, with the bed-plate C', provided with end plates, D', of the clamping-plate M', the handle-frame N, 40 the pintles O, and the springs Q, substantially as herein shown and described, and for the purpose set forth.

5. In a belt-tightener, the combination, with the bed-plate C', provided with end plates, D', 45 of the clamping-plate M', provided with a stud, R', on its inner surface, of the handle-frame N, the pintles O, the springs Q, and the buttons R, substantially as herein shown and described, and for the purposes set forth. 50

6. In a belt-tightener, the combination, with the bed-plate C', of the clamping-plate M', the handle-frame N, the slotted quadrant, plate, or strip S, the screw T, and the nut V, substantially as herein shown and described, and for 55 the purpose set forth.

7. In a belt-tightener, the combination, with the bed-plate C', of the removable end plate, D', provided with apertured lugs W, and of the pin Y, substantially as herein shown and 60 described, and for the purpose set forth.

JOHN F. WILSON.
